US0D1089460S

(12) **United States Design Patent** (10) **Patent No.:** **US D1,089,460 S**
(45) **Date of Patent:** **** Aug. 19, 2025**

(54) **STANDALONE STATIONARY BICYCLE FRAME**

(71) Applicant: **Zwift, Inc.**, Long Beach, CA (US)

(72) Inventors: **Thomas Owen**, London (GB); **Jack Darby**, London (GB); **Leanne Garner**, London (GB)

(73) Assignee: **Zwift, Inc.**, Long Beach, CA (US)

(***) Term: **15 Years**

(21) Appl. No.: **29/936,069**

(22) Filed: **Apr. 5, 2024**

(51) LOC (15) Cl. **21-02**

(52) U.S. Cl.

USPC **D21/663**

(57) **CLAIM**

The ornamental design of a standalone stationary bicycle frame as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a top, right, perspective view of the standalone stationary bicycle frame;

FIG. 2 is a bottom, left, perspective view thereof;

FIG. 3 is a right side view thereof;

FIG. 4 is a left side thereof;

FIG. 5 is a rear view thereof;

FIG. 6 is a front view thereof;

FIG. 7 is a top view thereof; and,

FIG. 8 is a bottom view thereof.

The broken lines shown represent unclaimed subject matter and form no part of the claimed design.

1 Claim, 7 Drawing Sheets
